VACUUM INDUCING CONSTRUCTION

Application filed September 29, 1927. Serial No. 222,705.

My invention relates to a vacuum inducing construction.

One of the objects of my invention is to provide improved means whereby the desired vacuum may be obtained from a connection with the intake conduit of an internal combustion engine, regardless of the position of the throttle.

The static pressure in intake manifold varies with the position of the throttle, the vacuum decreasing as the throttle is opened. To compensate for the decrease in static pressure I provide an induction device controlled by the velocity of flow of gas in the manifold which modifies the effect of the static pressure and gives the desired vacuum regardless of the throttle position.

In the drawings in which several forms of my invention are shown—

20 Figure 1 is a side-elevation showing my improved induction device installed in the intake manifold of an internal combustion engine;

25 Fig. 2 is a similar view showing a different installation for the induction device;

Fig. 3 is an enlarged view of the induction device showing details of construction;

Fig. 4 is a section on the line 4—4 of Fig. 3;

Fig. 5 is a longitudinal section view of a somewhat different form of induction device; and

Fig. 6 is a longitudinal sectional view of still another form of induction device.

Referring to the drawings in detail and first to Figs. 1 to 4, inclusive, the construction shown therein comprises the intake manifold 1 of an internal combustion engine having a trunk passage 2 leading from the carburetor, and two branch passages 3 and 4 leading from the trunk passage 2 to the engine cylinders, the induction device 5 being located in the trunk passage. This induction device may be connected by a suitable conduit 6 with any device in which it is desirable to maintain a vacuum such as the well known vacuum tank for use in supplying fuel to the carburetor on a suction operated device 6^a for operating a windshield cleaner 6^b. In these suction operated devices it is desirable that the suction should be maintained sub-

stantially constant regardless of the position of the throttle and this desirable condition will not be obtained if dependence is placed solely on the static pressure in the intake manifold as the suction due to this static pressure decreases materially when the throttle is open wide. It is common knowledge that suction operated windshield wipers frequently cease to operate when the throttle is opened wide, due to the decrease in suction. In order to compensate for this decrease in the static pressure I provide a suction inducing device comprising a tubular member having an enlarged head portion 8 located in the line of flow of the gas, indicated by arrows A, and a reduced shank portion 9 having a longitudinal passage 10 in communication with the suction conduit 6 and leading to a position adjacent the enlarged head, and having a transverse passage-way 11 which places said longitudinal passageway in communication with the intake conduit 3, said transverse passageway opening into the intake conduit at a place adjacent the juncture of the shank 9 and head 8. This transverse passage in Fig. 1 extends at right angles to the line of flow of gas in the intake manifold, so that the kinetic energy of the gas causes a reduction of pressure as it flows around the shank of the tubular member, modifying the effect of the static pressure on the suction conduit. Thus the effect of the variation of static pressure in the manifold on the suction conduit is compensated for by the effect due to the variation of velocity of flow of the gas in the manifold.

In assembly, the head 8 of the suction inducing device is inserted through a threaded opening in the manifold 1, and the threaded portion 12 of the suction inducing device is screwed into this threaded opening until a gas-tight fit is secured. The upper end of the suction inducing device is provided with a conical seat 13 for engagement with a flaring portion 14 of the suction conduit which is snugly held against this conical seat by means of a clamping nut 15 having a threaded engagement with the suction inducing device.

In Fig. 2 the suction inducing device is

shown as installed at the juncture of the two branch passages with the head facing the trunk passage 2 leading from the carburetor and throttle valve, so that the head faces the direction of flow from this trunk passage, indicated by arrows B. In this construction the flow of gas adjacent and around the head creates a suction back of the head due to the velocity of the gas which modifies the effect of the static pressure in the manifold.

The construction shown in Fig. 5 is similar to that just described except that the taper of the head 8 is concave instead of convex, which may be desirable for certain designs of intake manifold.

In Fig. 6 is shown a construction in which the suction device is made up largely of sheet material or tubular material. In this form a tubular member 16 of sheet material is fitted snugly into a suitably threaded bushing 17, the lower end being shaped and formed to provide the head portion 18 with lateral openings 19, and the upper end being flared outwardly at 20 for engagement with a conical seat portion 21 on the bushing 17. The connection with the suction conduit is effected by means of a clamping nut 22 and spacing washer 23, the suction conduit 6 having a portion 14 flared out to engage a conical seat portion 24 on the clamping nut 22, and the spacing washer 23 being located between the flared portion 20 of the tubular member and the flared portion 14 of the suction conduit.

The operation has been outlined in connection with the description of the construction.

An increase in the opening of the throttle valve has two compensating effects on the suction in the suction conduit. Opening the throttle increases the static pressure in the manifold and it also increases the velocity of flow of the gas in the intake manifold. The increase of static pressure tends to reduce the suction in the suction conduit but the increase of velocity of gas flow tends to increase the suction in the suction conduit. By properly designing the suction inducing device the resultant suction in the suction conduit may be maintained at the desired amount regardless of the throttle position.

I claim:

1. A suction inducing device having provisions for communication with a suction conduit and an intake conduit of an internal combustion engine comprising a tubular member having an enlarged head portion and a reduced shank portion, said shank portion having a longitudinal passage in communication with said suction conduit and leading to a position adjacent said enlarged head and having a transverse passage-way which places said longitudinal passage-way in communication with said intake conduit, said transverse passage-way opening into said intake conduit at a place adjacent the junction of the shank and head.

2. A suction inducing device having provisions for communication with a suction conduit and an intake conduit of an internal combustion engine comprising a tubular member having an enlarged head portion and a reduced shank portion, said shank portion having a longitudinal passage in communication with said suction conduit and leading to a position adjacent said enlarged head and having a transverse passage-way which places said longitudinal passage-way in communication with said intake conduit, said transverse passage-way opening into said intake conduit at a place adjacent the junction of the shank and head, said head having a tapering point facing the direction of flow in said intake conduit.

3. A suction inducing device having provisions for communication with a suction conduit and an intake manifold of an internal combustion engine comprising a tubular member having an enlarged head portion and a reduced shank portion, said shank portion having a longitudinal passage in communication with said suction conduit and leading to a position adjacent said enlarged head and having a transverse passage-way which places said longitudinal passage-way in communication with said intake manifold, said transverse passage-way opening into said intake manifold at a place adjacent the junction of the shank and head, said intake manifold having a passage leading from the carburetor and two branch passages leading in opposite directions from said first passage, the axis of said shank extending longitudinally with respect to the axis of said first passage-way.

4. A suction inducing device in communication with a suction conduit and intake conduit of an internal combustion engine comprising a tubular member having an enlarged head portion and a reduced shank portion, said shank portion having a longitudinal passage in communication with said suction conduit and leading to a position adjacent said enlarged head and having a transverse passage-way which places said longitudinal passage-way in communication with said intake conduit, said transverse passage-way opening into said intake conduit at a place adjacent the junction of the shank and head, said intake conduit having a screw threaded opening therein through which the head of said suction inducing device may be inserted into said intake conduit, and said suction inducing device having a screw threaded portion threaded into said opening.

In witness whereof, I have hereunto subscribed my name.
